In the Netherlands September 17, 1940

5 Claims. (CL 172—245)

In power apparatus the incandescent lamp provides an easy contrivance for the optical control over the synchronization of two alternating currents.

This invention has for its object to provide a device by means of which the same result can be obtained in cases where the available energy is far too low for the operation of an incandescent lamp. Such cases occur, for example, in calibrating the zero point of the dial of a low frequency oscillator, in admixing carrier wave at the receiving end of a wireless system, and in synchronizing ordinary alternating current power sources.

According to the invention, for this purpose use is made of a cathode-ray tube of the kind known as "magic eye" and intermediate the control electrode and cathode of the said tube is arranged an impedance which practically forms a by-pass for any frequencies higher than those that can still be seen by the eye.

If the difference-frequency formed from the two frequencies to be synchronized is superimposed on the control grid of the amplifier tube incorporated in the magic eye, a constant deflection of the luminous spot will be observed so long as the difference-frequency exceeds, for example, 20 cycles/sec. If, however, this frequency falls to below 20, flickerings are observed whose speed is reduced according as the point of synchronization is approached. On this point being reached the luminous image is again fully stationary.

The amplifier tube as used in my invention can be operated linearly and may therefore be used at any frequencies to amplify difference-frequency oscillations. This feature is particularly desirable in the case of a low-frequency oscillator.

In order that the invention may be clearly understood and readily carried into effect it will now be described more fully with reference to the accompanying drawing, in which one example of application of a low-frequency oscillator is diagrammatically shown.

Referring to the single figure of the drawing, 1 and 2 designate oscillators which set up the frequencies f_1 and f_2 respectively, at least one of these frequencies being variable through a more or less wide regulating range (e. g. 10 kilocycles). At a mixing stage 3 these frequencies are collected and the difference-frequency $f_1 - f_2$ is selected. This frequency is applied between the control grid 4 and the cathode 5 of the amplifier

part of a "magic eye" tube, this part comprising a pentode.

The screening grid 6 of this pentode whose anode is designated 7 is directly connected within the tube to the control electrode 8 of the "eye" proper whose fluorescent screen is designated 9.

The screening grid 6 is supplied across a resistance 10 and is in addition connected via a condenser 11 to the earthed point 12 whence a resistance 13 shunted by a large condenser 14 leads to the cathode 5.

The condenser 11 has such a capacity, e. g. 0.1 mfd., that it, in cooperation with the resistance 10, forms a by-pass for frequencies above 20 cycles/sec. between the screening grid 6 (and consequently also the control electrode 8) and earth so that the connection inter alia with the high capacity of the condenser 14 (for example 50 mfd.) appreciable potential fluctuations having a frequency at or above 20 cycles cannot arise between the control electrode 8 and the cathode 5. Elements 6 and 8 are, therefore, decoupled with respect to the cathode 5.

25 The oscillations applied between 4 and 5 and having the difference-frequency $f_1 - f_2$, which value may vary for example between 0 and 10,000 cycles/sec., are amplified by the pentode and used in known manner, if necessary after further amplification, for the purpose for which they are desired.

Since the tube V is substantially a dual purpose tube, it may at times be convenient to use its pentode section for amplifying the output 35 components from the mixer stage 3. In the pentode section, in addition to the common cathode 5 and the common grid 4, an anode 7, a screen grid 6 and a suppressor grid 21 are provided. Coupled to the output circuit which includes the anode 7 is a following amplifier stage 40 comprising a pentode tube 15, the input circuit of which includes resistors 16 and 17 connected between ground and the control grid. This control grid is coupled to the output circuit of tube 45 V by means of a capacitor 18. Tube 15 has the usual pentode electrodes, and its cathode is connected to ground through a cathode resistor 19. This resistor is preferably shunted by a capacitor 20. In the output circuit of tube 15 a load 50 resistor 22 is provided and, if desired, the output circuit may be coupled to a utilization device by means of a capacitor 23.

In order to calibrate the zero point of the dial f_1 is caused to approach f_2 , or conversely the difference-frequency $f_1 - f_2$ is made smaller and

smaller. So long as this difference is greater than 20 cycles per second variations of the luminous spot are not seen on the screen 8 because the electrodes 6 and 8 are sufficiently decoupled by the condenser 11 for this frequency.

The latter condition is, however, changed below 20 cycles/sec. and under these circumstances the difference-frequency becomes visible as a more or less slow flickering of the luminous spot. When the frequency of this flickering falls to zero the two frequencies f_1 and f_2 are indicated as exactly equivalent and the pointer of the meter of the difference-frequency should be set to cover the zero point.

I claim:

1. A synchroscope comprising a mixer stage having input circuits upon which alternating currents from two separate sources may be impressed, an output circuit for said stage, a discharge tube having an electron gun and a fluorescent indicating screen, and means including a control electrode in said tube coupled to the output circuit of said mixed stage effective only for producing a perceptible flicker effect which is a function of the difference-frequency resulting from the mixing of said alternating currents when they are caused to approach synchronism, and the difference frequency is no greater than 20 cycles per second.

2. A synchroscope according to claim 1 and including a wave trap connected to the input circuit of said tube and adapted to effectively bypass frequencies above 20 cycles per second.

3. A synchronism indicator system comprising a mixer stage, means for simultaneously impressing two input potentials on said mixer stage, said input potentials being derived from inde-

pendent sources of approximately the same frequency the synchronous relationship between which is to be indicated, a visual indicator discharge tube having a cathode, a fluorescent target anode and a control electrode effective to vary the area of fluorescent response to electronic emission in said tube, means for causing said tube to be controlled by output potentials from said mixer stage, and means for cancelling out any perceptible flicker response in said tube which would result from a phase rotation of potentials from one of said sources with respect to the other when the rate of said phase rotation is at least 20 revolutions per second.

4. A system for producing a perceptible flicker response which is useful to observe small differences between the frequencies of two electric sources, said system comprising an electronic mixed stage on which potentials from said sources are simultaneously impressed, a discharge tube of the type known as a "magic eye," said tube comprising a cathode, a control electrode, and a target anode rendered fluorescent by means of a suitably responsive coating thereon, means for applying output potentials from said mixer stage to the control of said magic eye tube, and means for neutralizing the flicker response on said target anode when the frequency difference between said sources is greater than 20 cycles per second.

5. A system according to claim 4 and including in the last said means a filter network consisting of parallel resistance and capacitance connected in the output circuit of said magic eye tube.

LOURENS BLOK.
